UNITED STATES PATENT OFFICE.

LOUIS J. BANKS, ANDRE D. ANDERSON, AND EDWIN S. LOVELL LOVELL, OF NATIONAL CITY, CALIFORNIA.

FLUID-AGITATOR.

1,216,540.

Specification of Letters Patent. Patented Feb. 20, 1917.

Application filed July 17, 1915. Serial No. 40,515.

To all whom it may concern:

Be it known that we, LOUIS J. BANKS and ANDRE D. ANDERSON, citizens of the United States, and EDWIN S. LOVELL LOVELL, a subject of the King of England, all residing at National City, in the county of San Diego and State of California, have invented certain new and useful Improvements in Fluid-Agitators, of which the following is a specification.

Our invention relates to an agitator for heavy fluids, liquids, slime and the like, and the objects of our invention, are; first, to provide a simple and economical means of 15 agitating and stirring and thus thoroughly mixing heavy fluids, liquids or slime and the like; second, to provide such a device that will take the heavier portion from the bottom central portion of a tank and discharge 20 it at the upper outer surface thereof; third, to provide a device of this class which is simple, economical of construction, durable, easily installed and does not readily get out 25 of order; and fourth, to provide an agitator of this class which operates by reason of centrifugal force.

With these and other objects in view as will appear hereinafter, our invention consists of certain novel features of construction, combination and arrangement of parts 30 as will be hereinafter described in detail and particularly set forth in the appended claims reference being had to the accompanying drawings and to the characters of reference 35 thereon which form a part of this specification, in which—

Figure 1, is a sectional view of our device showing some of the parts in elevation, and Fig. 2, is a sectional view of the revolving 40 portion of our device shown through A, B in Fig. 1.

Similar characters of reference refer to similar parts throughout the several views.

The receptacle 1, partitions 2, primer 3, 45 pump 4, decanting pipe 5, intake pipe 6, pump drive shaft 7, pulley 8 and frame 9, constitute the principal parts of our agitator.

The receptacle 1, is preferably round in 50 form and is provided with a conical shaped lower end. Mounted inside of this receptacle is an annular partition of smaller diameter than said receptacle so that its wall is spaced apart from the wall of said recep-

tacle some distance and it extends only approximately one-half the depth of said receptacle and it is supported by means of supports 2^a spacing apart the wall of the receptacle 1 from the partition 2. It is provided at its top edge with an inwardly extending flange 2^b to prevent the fluid from splashing over when emptied between said partition and the wall of the receptacle. Mounted centrally over the receptacle 1 is a frame 9 which is provided with bearings 9^a thereon which are mounted centrally over said receptacle and in these bearings is revolubly mounted the shaft 7 supported by means of the collar 7^a secured thereto. This shaft is provided on its lower end with a socket 7^b into which is inserted the upper end of the pump 4 and is secured thereto by means of the pin 7^c. The lower end of the pump extends to near the bottom of the receptacle and is suspended centrally in said receptacle on the bearings 9^a by means of the collar 7^a. This pump 4 consists of a hollow pipe extending to near the top of the receptacle and above the edge of the partitions 2 and flange 2^b, where it is provided with a hollow laterally extending arm 4^a which is provided with both a horizontal and vertical curve as shown, and extends outward so that its end is intermediate the wall of the receptacle 1 and the partition 2 so that any fluid or liquid discharged therefrom would be discharged between these two walls around the outer portion of the receptacle. The lower end of this hollow pipe is provided with a plurality of offset portions 4^b adapted to dig, mix and stir the heavy portion of the fluid and settling at the bottom when necessary and immediately above the digging portion are pipes 4^c which are oppositely disposed on the lower end of said pipe 4 and extend outwardly therefrom in curves as shown best in Fig. 2 of the drawing. Mounted on the bottom of the receptacle is the primer 3 which connects with a fluid receptacle and is adapted for priming the pump for starting and 95 consists of the pipe extending to the center of said receptacle then upwardly, the upper end 3^a being spaced apart from the lower end of the pipe 4, a short distance. This pipe 3 is provided with a valve 3^b adapted 100 for closing as soon as the pump is properly primed and in operation. The receptacle is filled by means of the inlet pipe 6 and if de-

105

sired, a continuous flow of liquid may enter said receptacle through said pipe and be decanted by means of the pipe 5, both of which when in operation add to the agitation of the fluid or liquid in said receptacle. Mounted near the bottom of said receptacle is a discharge pipe 10 for emptying said receptacle. Mounted on the shaft 7 is a pulley, adapted for a belt for connection with any driving mechanism.

Though we have shown and described a particular construction, combination and arrangement of parts, we do not wish to be limited to this particular construction, combination and arrangement but desire to include in the purview of our invention, the construction, combination and arrangement of parts substantially as set forth in the appended claims.

It is obvious that with this construction, there is provided a device that will carry the heavier portion of the fluid from the lower central portion of the receptacle to the upper outward portion and is operated by centrifugal force. The revolution of the pump 4 will force the fluid outwardly through the lateral arm 4^a discharging it between the wall of the receptacle 1 and the inner partitions 2 discharging it in a circle with its revolution and taking the contents of the receptacle from near the central portion by means of the pipes 4^c and the lower end of the pipe with the additional mixing of the offset portion 4^b; that if desired a continuous flow of liquid can be allowed to flow into the receptacle near the outer edge through the pipe 6 and be decanted through the pipe 5, thus increasing the agitation.

Having thus described our invention, what

we claim as new and desire to secure by Letters Patent, is:

1. In a centrifugal agitator, the combination of a receptacle, an annular partition of smaller diameter placed centrally therein, a centrifugal pump suspended centrally therein and adapted to revolve, comprising a pipe with a lateral hollow arm extending to near the outer portion of said receptacle.

2. In a centrifugal agitator, the combination of a receptacle, an annular partition of smaller diameter placed centrally therein, a centrifugal pump suspended centrally therein and adapted to revolve, comprising a pipe with a lateral hollow arm extending to near the outer portion of said receptacle and means for priming said pump consisting of a water pipe for conducting water to the lower end of said first mentioned pipe.

3. In a centrifugal agitator, the combination of a receptacle, an annular partition of smaller diameter placed centrally therein, a centrifugal pump suspended centrally therein and adapted to revolve, comprising a pipe with a lateral hollow arm extending to near the outer portion of said receptacle, means for priming said pump consisting of a water pipe for forcing water to the lower end of said first mentioned pipe, means for filling said receptacle, means for decanting therefrom and means for emptying said receptacle.

In testimony whereof, we have hereunto set our hands at San Diego, California this 12th day of July 1915.

LOUIS J. BANKS.
ANDRE D. ANDERSON.
EDWIN S. LOVELL LOVELL.
